(57) **CLAIM**

The ornamental design for an electrophoresis slab gel sample loading guide, as shown and described.

DESCRIPTION

FIG. 1 is a front perspective view of a first embodiment of an electrophoresis slab gel sample loading guide showing our new design.

FIG. 2 is back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a front perspective view of a second embodiment of an electrophoresis slab gel sample loading guide showing our new design.

FIG. 10 is a back perspective view thereof.

FIG. 11 is a front view thereof.

FIG. 12 is a back view thereof.

FIG. 13 is a right side view thereof.

FIG. 14 is a left side view thereof.

FIG. 15 is a top view thereof.

FIG. 16 is a bottom view thereof.

FIG. 17 is a front perspective view of a third embodiment of an electrophoresis slab gel sample loading guide showing our new design.

FIG. 18 is a back perspective view thereof.

FIG. 19 is a front view thereof.

FIG. 20 is a back view thereof.

FIG. 21 is a right side view thereof.

FIG. 22 is a left side view thereof.

FIG. 23 is a top view thereof; and,

FIG. 24 is a bottom view thereof.
